UNITED STATES PATENT OFFICE.

WILLIAM F. HENDRY, OF OSSINING, NEW YORK, ASSIGNOR TO MANHATTAN ELECTRICAL SUPPLY COMPANY, INCORPORATED, OF NEW YORK, N. Y., A CORPORATION OF MASSACHUSETTS.

DESIGN FOR A FLASH LIGHT.

Application filed July 30, 1924. Serial No. 10,323. Term of patent 14 years.

To all whom it may concern:

Be it known that I, WILLIAM F. HENDRY, a citizen of the United States, and a resident of Ossining, in the county of Westchester and State of New York, have invented a new, original, and ornamental Design for Flash Light, of which the following is the specification, reference being had to the accompanying drawing, forming part thereof.

The figure is a side elevation of the flash-light showing my new design.

I claim:

The ornamental design for a flash-light as shown.

WILLIAM F. HENDRY.
